UNITED STATES PATENT OFFICE.

EMMET N. DAVIDSON, OF BRECKENRIDGE, TEXAS.

COMBINATION TUBING SOCKET.

Application filed February 7, 1923. Serial No. 617,555.

To all whom it may concern:

Be it known that I, EMMET N. DAVIDSON, a citizen of the United States, residing at Breckenridge, in the county of Stephens and State of Texas, have invented certain new and useful Improvements in Combination Tubing Sockets, of which the following is a specification, reference being had to the accompanying drawings.

10 This invention relates to combination tubing sockets and has for an important object thereof a tubing socket adapted for use in removing broken parts of tubing from deep wells.

15 An important object of the invention is to provide means of this character which is capable of use with all types of tubing and of different forms of breaks of the tubing and which is likewise capable of use for 20 removing the broken ends of sucker rod lines and the like.

25 A further object of the invention is to provide a device of this character which provides in combination a means for gripping the casing exteriorly and a means for gripping the same interiorly, each of such means being so constructed as not to interfere with the normal operation of the other.

30 A still further object of the invention is to provide a device of this character from which the engaged tubing may be readily removed.

35 Another object of the invention is to provide a device of this character which may be readily lowered into the well casing for engagement with the tubing and which is so constructed that accumulated gas, oil or water within the well bore will not interfere with its insertion.

40 An additional object of the invention is to provide a device of this character which is readily removable from a socket engaging tubing which is broken off within the casing of the well to a socket for engaging tubing 45 which is broken off beneath the well.

50 It is well known to those familiar with the art that in the construction of deep wells after the bore is completed, the casing is elevated and a charge of high explosive placed in the lower end of the well beneath the casing and exploded to enlarge the opening beneath the casing and provide a pocket into which the oil or the like may flow, and tubing is then inserted in the well through

which the oil or the like may be pumped, 55 the lower end of this tubing projecting below the lower end of the well casing. This tubing in deep wells often becomes broken, sometimes breaking due to a cave-in of the shot hole, as the enlarged lower end of the 60 bore is generally termed, or is broken within the shot hole due to the fact that the movement of the tubing within the hole is not limited by the casing and accordingly 65 too great a strain is often applied to the 70 same with a resultant breakage. Furthermore, the tubing adjacent the upper ends of the casing is subjected to a terrific strain due to the weight of the tubing beneath and accordingly the tubing sections often part 75 at the couplings thereof. For this reason, the majority of the tubing employed in deep wells is of that type usually referred to as upset tubing, in which the ends of the tube have been enlarged by upsetting the 80 same to give an increased threading area for engagement by the coupling. These upset 85 ends of the tubing are difficult to engage by the ordinary form of socket which often takes what is commonly termed a foul grip 90 on the tubing resulting in slippage and consequent damage to the tubing and possibly to the derrick and workmen employed therein. An important object of this invention accordingly becomes to provide a single tool 95 which is capable of gripping the tubing within the casing or within the shot hole and which is so constructed as to render impossible the improper engagement thereof with upset tubing and which at the same 100 time is capable of use with the ordinary type of tubing.

These and other objects I attain by the construction and arrangement shown in the accompanying drawings wherein for the 95 purpose of illustration is shown a preferred embodiment of my invention and wherein like reference characters designate like parts throughout.

In the drawings:—

100 Figure 1 is a vertical sectional view through a socket constructed in accordance with my invention showing the head, barrel, slip socket and spear in use;

Figure 2 is a similar view showing the 105 wing socket, spear and head in use;

Figure 3 is a section taken on the line 3—3 of Figure 1; and

Figures 4, 5, 6, 7 and 8 are partially diagrammatic views showing various manners of connecting the tool for different uses.

Figure 9 is a section on line 9-9 of Figure 2.

Referring now more particularly to the drawings, the numeral 10 indicates a head which is adapted at its upper end for engagement with a tool line, as indicated at 10 11. At its lower end the head is provided with a reduced extension 12 which is exteriorly screw-threaded, as at 13, for engagement with a barrel 14. The head has formed in the lower face of the reduced extension 12 thereof a socket 15 for the reception of a tubing spear 16. The head has formed therethrough ports 17 opening through the head adjacent the upper end thereof and through the lower end of the 20 extension 12.

The barrel 14 is made of a desired length and is provided at its lower end with a reduction 18 of the same external diameter as the reduced extension 12 and which is exteriorly screw-threaded for interchangeable engagement with a slip socket 19 or a wing socket 20. It will be obvious that the slip or wing sockets 19 and 20 are interchangeably engageable with the lower end of this 30 barrel or with the reduced extension 12 of the head 10. The lower end of the reduced portion 18 of the barrel has its lower face upwardly and inwardly inclined, as indicated at 21. The wall of the barrel has formed therein ports 22, one of which is arranged so that the gripping part 23 of the spear 16 may be observed to note whether the same is operating properly or no. These 35 ports and the ports 17 of the head 10 serve to permit the passage of fluid, gas or the like when the device is being lowered into or withdrawn from the casing C of the well.

The spear 16 is made of a diameter such that it enters the tubing with which it is to coact with but a slight clearance and has its lower end rounded, as indicated at 45 24, so that it may readily enter such tubing. The upper end of the spear 16 immediately adjacent the threaded portion thereof is formed for engagement in the socket 15 of the head, is provided with an enlargement 25 having a downwardly directed shoulder 26 against which the upper end of the tubing will abut to limit its movement 50 and expose a portion of the spear for engagement by a wrench so that the spear may be removed from the head 10. The exterior of the enlargement 25 is polygonally formed for such engagement. Adjacent its lower end the spear 16 is formed with a recess having a horizontally disposed upper wall 27 and an upwardly and inwardly inclining side wall 28. This side wall has formed therein a dove tail groove 29 which 55 is engaged by a dove tail lug 30 formed

upon the gripping element or slip 23. Adjacent the lower end of the groove, a key 31 extends transversely thereof preventing the removal of the slip from the lower end of the groove. The slip 23 is substantially triangular in form and has its outer face curved to correspond to the curvature of the tubing with which it is to coact and formed with teeth 32 for engaging the tubing. This slip is of less length than the recess 70 and is of such size that when located at the lower end of the recess its outer face projects beyond the plane of the outer face of the spear so that the teeth thereof may engage the tubing, the combined widths of the 75 spear and slip when the slip is in the lower-most position being greater than the internal diameter of the tubing with which the spear is to coact and the combined widths of the spear and slip when the slip is at 80 the upper end of the recess being less than such diameter.

The slip socket 19 is provided with an external reduction 33 which is exteriorly screw-threaded for interchangeable engagement with a band 34 or with the wing socket 20. The lower end of the slip socket has its lower face upwardly and inwardly inclining, as indicated at 35, and the band 34 has its lower end similarly inclined, as indicated at 36, and is of a size rendering these inclined faces continuous or complementary when the band is in the proper position. The bore of the slip socket tapers downwardly, as indicated at 37, and has formed in the wall thereof substantially vertically extending dove tail grooves 38 which are engaged by similarly formed lugs 39 upon slips 40. The outer faces of these slips or those which will be disposed 100 toward a tubing entering the socket are vertical and are curved to correspond to the curvature of the casing with which they are to coact, these faces being formed with teeth 41 for engaging the tubing. The slips 105 40 are removable from the socket 19 so that they may be interchanged to permit coaction of the socket with tubing or rods of different external diameters. The wing socket 20, which as above set forth is capable of interchangeable engagement with the head 10, barrel 14 or slip socket 19, is in the form of a barrel 42 having a bore 43 of the same diameter as the bore of the barrel 14 and provided with ports 44 corresponding to the ports 22 of the barrel 14 and through which the slip 23 may be observed. The lower end of the barrel is split, as indicated at 45 and the bore of such lower end enlarges downwardly, as indicated at 46. The wings 47 formed by splitting the wing socket are resilient and have a tendency to spring outwardly to a diameter greater than the diameter of the casing C with which the socket is designed to co- 115 120 125 130

act. The lower ends of these wings have their edges formed in a spade shape, as indicated at 48.

In fishing for tubing T of ordinary construction which is broken off within the casing C of the well, the slip socket 19 provided with slips of the proper size may be attached either directly to the head 10 and the spear 16 omitted or this socket may be attached 10 to the lower end of the barrel 14 which is in turn engaged with the head and the spear 16 employed. The band 34 is employed upon the socket when the device is put to this use and as the device is lowered into the 15 well, the tubing engaged by the inclined lower edges 35 and 36 of the socket 19 and band 34 will be guided into the bore 37 of the socket. The slips 40 employed in the socket 19 on such an occasion will be of such 20 size that when in the lowermost position they restrict the bore 37 to a diameter less than the diameter of the tubing to be engaged. The tubing engaging against these 25 slips, will force the same upwardly, lowering of the device being continued until the tubing engages against either the head 10 or the shoulder 26 at the upper end of the spear 16 if the same be employed. The device is then hoisted and the slips which will be 30 maintained in engagement with the side walls of the tubing by gravity will be forced downwardly by the engagement of their teeth with the tubing so that they wedge in against the tubing and secure a very firm 35 hold thereon. If the spear 16 is being employed, the slip 23 thereof will move downwardly causing the spear body to engage against the internal diameter of the bore at one side and the slip at the opposite side, 40 providing a very firm grip so that the tubing may be hoisted from the well.

When employed for removing tubing having upset ends, the spear 16 is preferably employed together with the barrel 14 and the 45 slip socket 19. With this type of tubing, the slips 40 employed are preferably of such size that when in their lowermost position, while immediately adjacent the outer face of the casing, they do not actually engage there- 50 against. The enlarged head of the tubing in passing into the bore of the slip socket elevates these slips until they are spaced apart a sufficient distance to permit the passage of the head when they are dropped by gravity 55 to the lower ends of the grooves. When in this position they restrict the bore 37 of the slip socket to such an extent that the head T' of the casing cannot possibly pass therethrough. The casing moving upwardly en- 60 gages the lower end of the spear and is guided thereon and finally comes to rest abutting the shoulder 26. The device is then elevated and the slip 23 of the spear will engage the inner wall as hereinbefore de- 65 scribed, locking the spear and tubing to-

gether so that the tubing is being elevated by the spear. When being so elevated, motion of the tubing T from side to side is prevented by the slips 40, thus preventing any undue side strain being placed upon the 70 spear to bend or otherwise injure the same. If the slip 23 of the spear fail to work, the head T' of the tubing will come to rest upon the upper ends of the slips 40 so that the 75 tubing will be supported.

When employed for removing tubing which is broken off below the lower end of the casing, a wing socket 20 is employed and may be employed either with the spear alone or with the spear and slip socket 19 as 80 desired. When the device is assembled it is lowered into the casing and reaching the lower end of the casing, the wings 47 expand to engage the walls of the shot hole and to receive therebetween the upper end of 85 the broken section of tubing. This section will then be guided upwardly into the bore 43 of the wing socket and if the spear alone is employed and the wing socket is engaged directly with the head, the spear engages the 90 tubing to elevate the same. If the socket 19 is employed alone, the tubing passes upwardly through the bore 43 into the bore 37 of the socket where the tubing is engaged by the slips 40. Where both the spear and 95 socket are provided, the barrel 14 is used and the operation in engaging the tubing is similar to that above described for engaging tubing broken off within the casing.

From the foregoing it is believed to be ob- 100 vious that a combined socket of this construction is readily adaptable for engagement with tubing of the usual construction whether the same be broken off within or below the casing C of the well. It will further- 105 more be obvious that by omitting the spear, the socket 19 may be employed for removing broken rods and the like. Many changes being possible in the specific construction of the device as hereinbefore set 110 forth, I do not limit myself to such specific structure except as hereinafter claimed.

I claim:

1. Means for removing broken tubing from well casings including a head adapted 115 for attachment to a drill line, a spear en- gaged with the head of less diameter than the internal diameter of the casing to be en- gaged, a slip carried by the spear normally maintained by gravity in a position where 120 its outer face projects beyond the outer face of the spear, such outer face of the slip being provided with gripping teeth, said slip being movable upon the application of upward pressure thereto to a position where 125 it is concealed within the spear, and means carried by the head for guiding tubing for engagement by said spear.

2. Means for removing broken tubing from well casings including a head adapted for 130

attachment to a drill line, a spear engaged with the head of less diameter than the internal diameter of the casing to be engaged, a slip carried by the spear normally maintained by gravity in a position where its outer face projects beyond the outer face of the spear, such outer face of the slip being provided with gripping teeth, said slip being movable upon the application of upward pressure thereto to a position where it is concealed within the spear, and means carried by the head for guiding tubing for engagement by said spear, said spear being removably connected with said head and being provided adjacent its upper end with an enlargement of greater size than the diameter of the tubing with which the spear is adapted to coact, said guiding means being removable from said head while said spear is engaged with tubing.

3. In a tool of the type described, a head provided in its lower end with a spear receiving socket, a barrel engageable with said head, and a slip socket interchangeably engageable with the barrel of said head.

4. In a device of the type described, a head provided upon its lower end with a reduced threaded extension, a barrel and a slip socket each having at its lower end a reduced extension of the same diameter as the reduced extension of the head and screw-threaded and each provided at its upper end with internal screw-threads engageable with the screw-threaded extension of the head, the lower faces of the extension of the barrel and slip socket being upwardly and inwardly inclined, and a band interchangeably engageable with the last named extensions and having an inclined lower face

complementary to the inclined lower face 40 of the extension.

5. In a tubing fishing tool and in combination with a head formed at its lower end to provide one member of a coupling and in its lower end with a spear receiving socket, a 45 barrel, a slip socket and a wing socket each provided at its upper end with a coupling member complementary to the coupling member of the head, said barrel and slip socket being provided at their lower ends 50 with coupling members identical with the coupling member of the head, the lower faces of the lower coupling members of the barrel and slip socket being upwardly and inwardly inclined, and a ring interchangeably engageable with the last named coupling members and having an inclined lower face 55 complementary to the inclined lower faces of the coupling members.

6. In a tubing fishing tool and in combination with a head formed at its lower end to provide one member of a coupling and in its lower end with a spear receiving socket, a plurality of tubular guides including a 60 slip socket provided at their upper ends 65 with coupling members complementary to the coupling members of said head and at their lower ends with coupling members similar to the coupling members of said head, and means selectively engageable with the lower coupling members of said guides providing at the lower ends thereof when applied an upwardly and inwardly inclined surface to direct and engage tubing into 70 said guides.

In testimony whereof I hereunto affix my signature.

EMMET N. DAVIDSON.
